UNITED STATES PATENT OFFICE.

WILLIAM M. WOODWARD, OF SUMTERVILLE, ASSIGNOR OF TWO-THIRDS TO
JAMES H. CURRY, OF SUMTER COUNTY, AND JOHN L. CARNEY, OF
MARION COUNTY, FLORIDA.

SPRING-MOTOR.

SPECIFICATION forming part of Letters Patent No. 351,894, dated November 2, 1886.

Application filed July 12, 1886. Serial No. 207,819. (No model.)

To all whom it may concern:

Be it known that I, WILLIAM M. WOODWARD, of Sumterville, in the county of Sumter and State of Florida, have invented certain new and useful Improvements in Spring-Motors, of which the following is a specification, reference being had to the accompanying drawings.

My invention relates to means for controlling, directing, and utilizing the force of a series of coiled springs for the propulsion of street-railroad cars, or other vehicles or carriages upon level or inclined grades, for the propulsion of light water-craft, and to operate various machinery.

15 My general plan is to have a series of coiled springs capable of being wound up one at a time, or two or more at a time, or all together, and also capable of expending their force one at a time, or two or more at a time, or all together, to rotate a train of gears, and a driving-wheel with varying power controllable by an operator according to what may be required in practice.

25 In the accompanying drawings, illustrating my invention, Figure 1 is a plan view of my improvements applied to a street-car. Figs. 2, 3, 4, 5, 6, 7, and 8 are views of detached parts, drawn on a larger scale for better illustration, Fig. 2 showing one side of a block, X, in which 30 is a cavity; Fig. 3 showing one side of a spring winding wheel; Fig. 4 showing the other side, and also an indicator connected therewith; Fig. 5 showing a section of one of the gear-wheels V on its shaft; Fig. 6 showing a section 35 of one of the loose pinions on its shaft; Fig. 7 showing a jointed lever and spring, and Fig. 8 showing clutch-levers.

40 Referring to the letters upon the drawings, in aid of a description in detail of my improvements in the form illustrated as applied to a street-car, A indicates the frame of the car; B, the driving-wheels, and C their axle, all of ordinary construction, the other truck not being illustrated.

45 D indicates the spring-winding shaft carrying sliding clutches E and loose pinions F.

G is a beveled gear-wheel upon the end of shaft D, meshing with a beveled pinion, H, upon the rotary shaft I, having another beveled

50 pinion, K, on its opposite end, which gears with a beveled pinion, L, upon a vertical shaft, M, which may be provided with a crank for turning it by hand.

N indicates a series of levers for operating the clutches upon shaft D. (See Fig. 8.) 55 Each of these levers is connected with a sliding clutch, E, by means of a link, O, and elbow-lever P, pivoted at Q. As each lever is raised, a clutch, E, will be disengaged from a loose pinion, F, and as it is lowered it will be 60 engaged therewith. By this means the pinions F, or any one or more of them, can be at will rigidly fixed to the shaft D, so as to turn therewith. The loose pinions F respectively mesh with the spring-winding wheels R, to which 65 the outer ends of the springs S are secured by a hook, as shown in Fig. 4, or in any usual or suitable way. The inner ends of the coiled springs are secured by means of a hook, T, as shown in Fig. 5, or otherwise, to the hubs U of 70 gear-wheels V. These gear-wheels V, like the spring-winding wheels R, it should be noted, are loose on the fixed shaft Y, and while the inner ends of the main springs are secured to the hubs of the wheels V, and their outer ends 75 are secured to the wheels R, it is practicable to wind up the springs by proper mechanism for turning wheels R, and then their strain or force will be exerted so as to tend to turn the wheels V, which, being properly geared to 80 other wheels, will communicate the force of the springs to them, and it may thus be utilized to propel a car or drive machinery. The function of the wheels V is to receive and communicate to other gearing the force of the 85 springs when they are wound up.

Figs. 3 and 4 represent opposite side views of the spring-winding wheels R. In Fig. 3 is illustrated a ratchet-wheel, W, which may be cast integral with or made fast to each wheel 90 R, and placed within a cavity in one side of each block X, through which pass the fixed shafts Y and Z. Within the same cavity is a spring-pawl, a, which engages with the ratchet on each wheel, so that as the wheels are turned to wind up the main springs the ratchets and pawls hold them as usual in clock mechanism. 95

b in Fig. 3 indicates a pawl pivoted to a

spring-winding wheel, R, having a pin, c, at one end, which passes through a curved slot, d, in the wheel and projects out on the other side, as indicated in Fig. 4, underneath the outer end of the last coil of the spring. Each wheel R is provided with these parts, and each block is provided with notches or ratchet-teeth e. The result is, that as the spring-wheels are wound up the pivoted pawls b will be turned so as to engage at the proper time with one of the notches or ratchet-teeth e in the block X, to prevent the spring from being wound up too far.

f indicates a series of pinions, and g a series of gear-wheels, each pair being rigidly connected together and loose upon the shaft Z. The pinions f gear with the gear-wheels V, and are driven, as well as the wheels g, by the wheels V.

h indicates a series of pinions loose on the shaft i and meshing with the wheels g.

k indicates a series of sliding clutches upon the shaft Z, provided with springs l, tending to keep them engaged with the pinions f.

m indicates a series of sliding clutches on the shaft i.

n is a series of levers, each connected, by means of link o, elbow-lever p, link q, elbow-lever r, link s, and pivoted lever t, with the clutches k and m. When a lever n is raised, it will operate one set of these links and levers, so as to disengage clutch k, forcing back its spring, and engage clutch m. When one of these levers is lowered, one of the clutch-springs l will cause one clutch k to engage and one clutch m to disengage. Whenever the clutches k are engaged they prevent the spring-power from running down, and whenever they are disengaged the spring-power is transmitted to rotary shaft i and the gear-wheel u upon its end. This gear-wheel u meshes with a pinion, v, upon a rotary shaft, w, provided with gear-wheels x y, fixed on said shaft. The wheel x gears with a pinion, z, loose upon a shaft pin, A². The pinion z gears with a loose pinion, B², on the axle C of the driving-wheel B. The wheel y gears with the loose pinion C² upon the axle C. Between the pinions B² and C² is a sliding clutch, D², adapted to engage with one or the other pinion, according to the direction of movement of the car, and thus rigidly connect the pinions, one at a time, with the axle C of the driving-wheel.

E² is a pull cord or wire passing over a pulley, F², and connecting with one end of an elbow-lever, G², pivoted at H², and engaging with the clutch D² to operate it.

I² is a spring, which is fastened at one end to the frame and at the other to one arm of the elbow-lever G², tending always to keep the clutch in engagement with the pinion B². When it is desired to engage the clutch with the pinion C², it is only necessary to pull the cord E². The object of this pull-cord and the gearing between shaft w and axle C and the clutch D² and its shipping mechanism is to reverse the action of the spring-power upon the

axle C and driving-wheels at will, so that the car or machinery being driven may be run in opposite directions at pleasure, and be always subject to the instant control of the attendant or operator.

The sliding clutch D² is so adjusted between the loose pinions B² and C² that it will always partially engage with one before it is entirely disengaged from the other, the slipping always taking place when the machinery is at rest or the car comes to a stop. The object of this adjustment is to prevent the springs from suddenly running down during the slipping operation.

K² is a sprocket-wheel upon the rotary shaft D, which may be a part of the beveled gear-wheel G. L² is a sprocket-pinion on the rotary shaft M². N² is a chain or sprocket belt. O² is a double sprocket-wheel fixed on the shaft M², and connected by chain bands, respectively, with the loose sprocket-pinions P² on the axle C and Q² on the fixed pin-shaft R². All this sprocket-gearing, being of ordinary construction and well known, is therefore not illustrated in detail, but only in outline diagrammatically, and its construction and operation will be understood without more explanation by all skilled in the art of making and using common and well-known gearing.

S² is a pinion rigidly connected with the sprocket Q², and meshing with a loose pinion, T², on the axle C. Between the sprocket-pinion P² and the loose pinion T² is a sliding clutch, U², provided with an elbow shipping-lever, V², pivoted at W², and actuated by a pull-cord, X², and spring Y², such as already described, and connected with the opposite end of axle C. The object of this clutch and pinions and sprocket-wheels and bands is to utilize the momentum of a car or machinery to wind up the springs. Normally the clutch U² stands out of engagement with the sprocket-pinion P² and loose pinion T²; but when engaged with either one it fixes that one to the axle C. Thus when the car is running in one direction on a downgrade by force of gravity, by means of the pull-cord X², the clutch can be engaged with the pinion T² by pulling against the force of the spring Y². Then by means of the sprockets and their bands motion will be communicated to rotary winding-shaft D, and one or more of the springs may be wound up, the action of the springs in the meantime having been cut off by means of levers n, so that they no longer operate to propel the car or machinery. Again, when it is desired to engage the clutch U² with sprocket-pinion P², the cord X² can be released or lowered, and spring Y² will engage the clutch with pinion P². Levers such as shown may be applied to pull cords E² and X² to work them, if desired. By that means clutches U² and D² can be adjusted and placed quickly at will.

It is desirable to have an indicator to show how much each spring is wound. Such a mechanism is shown in Fig. 4, where A³ is a pin on the spring-winding wheel, and B³ a

pivoted lever, one arm of which is in the path of the pin, and the other of which is connected to a wire or cord, C³, that is attached to the end of a lever, D³. E³ is a spring, which may be a continuation of the wire C³, and serves to keep levers B³ and D³ in place, to be operated by pin A³. Lever D³ is jointed and provided with a spring, F³, pressing on the short pivoted end piece or latch G³. (See Fig. 7.) H³ is a toothed wheel connected with an index pointer, h⁴, working over a dial with numbers on it (not illustrated) in the ordinary way. Each time the winding-wheel makes a revolution the pin and levers will cause the wheel H³ and the pointer to move the distance of one notch, and thus the degree of winding of the spring may be shown on the dial. The spring E³ will adjust the levers to place again, and the jointed or latch part G³ of the lever D³ will slip back over one tooth against the force of spring F³, (which should be weaker than spring E³), and there assume its place by force of spring F³ behind another tooth, ready for making another push. On the opposite side of the notched wheel H³ is a similar system of springs and levers, operating in the same way, in connection each with a gear-wheel, V, provided with a pin, A', as shown in Fig. 1. The object of this second system is to operate the indicator when the spring is unwinding. In order to hold the notched wheel and indicator in place securely, I provide a slide, K³, working in a slot in a plate, L³. The slide is provided with a spring, M³, tending to keep it down in one of the notches of the wheel H³. The spring of this slide is just sufficient for that purpose, and not strong enough to materially resist the turning of the notched wheel.

In Fig. 6 is illustrated a method of holding the loose pinions in place on their shafts, N³ being two disks on opposite sides of the pinion, held in place by means of set-screws O³ to the shaft.

Fig. 5 is a sectional detail of the gear-wheel V and its hub, showing anti-friction bearings P³, which may be either fixed or loose on shaft Y; but these are ordinary anti-friction devices, and form no part of my improvement. These can be conveniently removed and replaced when worn.

By means of this apparatus it will be seen, for example, that for the purpose of running a street-car the entire power of a compact series of springs can be stored by simply winding them up simultaneously at a station. At the same time their force can be held so that it will not tend to move the car. Whenever it is desired to start, an operator can apply as much force as necessary to start the car, then can cut out or withdraw as much force as it may be proper to dispense with as soon as the car is in motion. When it is desired to stop, the entire force of the springs can be cut off from its propelling action, and the motion of the car utilized to wind up the springs, or such of them as may be wholly or partially un-

wound, until the car stops. If necessary, ordinary brakes may be employed also to effect stopping. Then when an upgrade or a heavy load, or both, require the addition of propelling force, more springs, or all of them, if need be, can be instantly brought into action. In going down grades, all the spring propelling force can be cut off and adjustments instantly made, so that the motion of the car will serve to wind up one or more springs, or all of the springs that may be wholly or partially unwound. The same advantages may be had in the propulsion of any other vehicle, or in the propulsion of small water-craft, or in the running of any machinery suitable or advantageous to be propelled by spring-motor power.

Many mere changes of form may be introduced in the embodiment of my invention without departing from its substance, and I therefore do not confine my improvements to the forms in detail illustrated and described.

The spring-winding shaft D may be wound up by power applied, in any usual manner, through ordinary gearing. For example, the chain belt N² may be removed from the sprocket-pinion L² and applied to a chain-wheel driven by a stationary engine while it is also upon sprocket-wheel K².

What I claim to be new, and desire to secure by Letters Patent of the United States, is—

1. The combination, with a suitable supporting-frame, of shaft Y and a series of coiled springs and spring-winding wheels thereon, a spring-winding shaft, D, and pinions and clutch mechanisms thereon for winding up the springs, and a train of spring-driven gears and shafts, Z and i, with a series of clutch mechanisms thereon, whereby the springs may be singly or together wound and their power singly or together expended, substantially as set forth.

2. The combination, with a suitable supporting-frame, of shaft Y and a series of coiled springs and spring-winding wheels thereon, a spring-winding shaft, D, and pinions and clutch mechanisms thereon for winding up the springs, and a train of spring driving gears and shafts, Z and i, with a series of clutch mechanisms thereon, and gears connecting shaft i and axle C, and the clutch D² and its clutch shipping mechanism, substantially as set forth.

3. The combination, with a suitable supporting-frame, of shaft Y and a series of coiled springs and spring-winding wheels thereon, a spring-winding shaft, D, and pinions and clutch mechanisms thereon for winding up the springs, and a train of spring driving gears and shafts, Z and i, with a series of clutch mechanisms thereon, gears connecting shaft i and axle C, clutch D², and its clutch shipping mechanism, with the sprocket wheels, chains, and gears for winding up the springs by the motion of the car or mechanism, substantially as set forth.

4. The combination, with shafts Y and Z, of spring-winding wheel R and its block X,

having in its cavity ratchet-wheel *w* and spring-pawl *a*, substantially as set forth.

5. The combination, with spring-winding wheel *R*, having a curved slot, *d*, and its spring, of pivoted pawl *b*, pin *c*, and block *X*, provided with notches or ratchet-teeth *e*, substantially as set forth.

6. The combination, with the spring-winding wheel having the pin *A*³, pivoted lever *B*³, cord *C*³, jointed lever *D*³, having spring *F*³, spring *E*³, and toothed wheel *H*³, with a dial and pointer, substantially as set forth.

7. The combination, with the spring-winding wheel having the pin *A*³, pivoted lever *B*³, cord *C*³, jointed lever *D*³, having spring *F*³, 15 spring *E*³, toothed wheel *H*³, with a dial and pointer, and spring-slide *K*³, substantially as set forth.

In testimony whereof I have hereunto subscribed my name.

WILLIAM M. WOODWARD.
